UNITED STATES PATENT OFFICE

2,154,299

REFRIGERATOR

Harley H. Bixler, Schenectady, N. Y., assignor to
General Electric Company, a corporation of
New York

Application May 31, 1935, Serial No. 24,196

10 Claims. (Cl. 62—116)

My invention relates to refrigerators.

It is frequently desirable, especially in domestic installations, to provide a single refrigerator having separate compartments in which various types of articles may be preserved under the particular conditions of temperature and humidity best suited thereto. A freezing compartment should be provided in which ice cubes, or the like, may be frozen in suitable trays and in which meat, and the like, may be preserved at a temperature below 32° F. At least one other compartment should be provided in which vegetables and other foods may be preserved at a temperature above 32° F. and in air of sufficiently high humidity to prevent excessive dehydration thereof.

Refrigerating machines of the primary-secondary type are particularly adapted for use in refrigerators of the type described. In refrigerating machines of the primary-secondary type a primary refrigerant circuit is provided which includes a primary evaporator supplied with liquid refrigerant from a suitable source or refrigerant circulating device of any of the well-known types. The secondary refrigerant circuit also includes an evaporator. The refrigerant passages of the two refrigerant circuits are not in communication with each other, but portions of the two refrigerant circuits are, however, arranged in heat exchange relationship, so that the primary evaporator abstracts heat from the refrigerant contained in the secondary refrigerant circuit. Because of the independence of the circulatory systems of the two refrigerant circuits, it is possible to maintain the evaporator contained in each circuit at a different temperature from the other. The primary evaporator may be conveniently utilized for cooling the freezing compartment and the secondary evaporator may be utilized for cooling the cooling or food storage compartment.

It is an object of my invention to provide a refrigerating machine of the primary-secondary type having an improved arrangement for controlling the temperatures produced by each of the several evaporators included in the machine.

It is a further object of my invention to provide a refrigerator of the type described including a refrigerating machine of the primary-secondary type having an improved arrangement of the parts thereof which is efficient in operation and which is economical to manufacture.

Another object of my invention is to provide a refrigerating machine having an improved arrangement for preserving vegetables and similar

perishable articles which are particularly sensitive to the effects of dehydration.

Further objects and advantages of my invention will become apparent as the following description proceeds and the features of novelty 5 which characterize my invention will be pointed out with particularity in the claims annexed to and forming a part of this specification.

For a better understanding of my invention, reference may be had to the accompanying drawings in which Fig. 1 is a side elevation, partly in section, of a refrigerator embodying my invention, the top thereof being broken away; Fig. 2 is a detail sectional view of a control valve included in the refrigerator shown in Fig. 1; 15 Fig. 3 is an exploded view of the refrigerator shown in Fig. 1 the lower portion thereof being partly cut away; and Fig. 4 is an enlarged exploded view, partly in section, of the arrangement for transferring heat between the primary 20 and secondary refrigerant circuits included in the refrigerating machine shown in Figs. 1 and 3.

Referring to the drawings, in Fig. 1 I have shown a refrigerator embodying my invention including a smooth walled rectangular cabinet 25 made up of separable upper and lower sections 10 and 11 respectively. The upper section 10 of the cabinet is provided with an outer sheet metal shell 12 and has a rectangular relatively low temperature or freezing compartment 13 30 formed therein by a rectangular sheet metal liner 14. The side walls and top of the liner 14 are surrounded by heat insulation 15. A plate 12a of insulating material provided with a central rectangular opening 12b forms the 35 bottom of the upper cabinet section 10. The lower section 11 of the cabinet which supports the upper section 10 is provided with an outer rectangular relatively high temperature sheet metal shell 16 and has a rectangular cooling or 40 food storage compartment 17 formed therein by a rectangular sheet metal inner liner 18. The side walls and bottom wall of the liner 18 are surrounded by heat insulation 19. The upper edge of the shell 16 is provided with an inturned 45 peripheral flange 20 on which an adjacent in-turned flange 21 formed on the shell 12 rests. A recess 22 is formed in the flange 21 extending entirely about the same and a rectangular rubber gasket 23 is mounted therein. The rubber 50 gasket is firmly retained on the upper surface of the flange 20 by the weight of the upper section 10 of the cabinet. An air-tight joint is thus formed between the upper and lower sections of the cabinet and in that way the ingress 55

of air to the space between them is prevented. It is desirable thus to exclude moisture-laden air from the space between the walls of the cabinet containing insulation both to prevent the formation of frost therein and also to prevent the deposit of moisture in the insulation, because the insulation is usually made of some dry fibrous material the heat insulating properties of which are radically reduced when it absorbs a substantial amount of moisture. A pair of pins 21a provided in the flange 21 engage complementary holes 20a formed in the flange 20 thus preventing lateral displacement of the upper cabinet section 10 with respect to the lower section 11. The cabinet, described above, is provided with a primary-secondary type refrigerating machine in which the primary evaporator is utilized for cooling the freezing compartment 13 and abstracting heat from the refrigerant in the secondary circuit while the secondary evaporator is utilized for cooling the cooling compartment 17. A refrigerant liquefying unit which supplies liquid refrigerant to the primary evaporator is also mounted on the separable top cabinet section 10. The provision of a refrigerator including a cabinet made up of separable upper and lower sections containing a freezing compartment and a cooling compartment, respectively, and also comprising a primary-secondary type refrigerating machine for cooling said compartments is not my invention, but is the invention of Christian Steenstrup and is described and claimed in his Patent No. 2,101,656, granted on December 7, 1937, and assigned to the General Electric Company, the assignee of my present invention. My present invention relates to an improved arrangement for controlling the temperature of the compartment cooled by the secondary evaporator, the ventilation of the refrigerator, and an improved heat exchange arrangement between the primary and secondary circuits.

In the refrigerating machine illustrated, gaseous refrigerant, such as sulphur dioxide, is compressed by a motor driven compressor contained in a hermetically sealed casing 24 and is supplied to an air cooled condenser 25 which surrounds the casing 24, the condenser and casing being cooled by natural draft. Liquefied refrigerant is discharged from the condenser 25 through a conduit 26 and passes through a flow controlling float valve 27 to a conduit 28 through which it is supplied to a primary evaporator 29, which is of the flooded type. The primary evaporator 29 includes a cylindrical horizontal header 30 and a series of depending refrigerant circulatory conduits 31, which communicate at their upper ends with the header 30 below the normal liquid level therein. The header 30 is maintained about half full of liquid refrigerant, the refrigerant circulatory passages 31 thus being maintained flooded with liquid refrigerant. The refrigerant circulatory passages 31 are arranged in good thermal contact with the metallic inner liner 14 of the freezing compartment 13 and are distributed over the surface thereof, so that the entire surface of the inner liner 14 is maintained at a substantially uniform temperature. The liquid refrigerant contained in the refrigerant circulatory passages 31 is vaporized by the absorption of heat from articles contained in the freezing compartment 13, and also by the absorption of heat transferred thereto from the secondary evaporator, as hereinafter described. The bubbles of vaporized refrigerant flow upwardly through the refrigerant circulatory pas-

sages 31 of the primary evaporator 29 to the header 30 thereof where they are collected above the level of the liquid refrigerant therein. The vaporized refrigerant collected in the header 30 is returned to the refrigerant compressor in the casing 24 through a suction line 32, which is connected to the top of the header 30 and above the level of the liquid refrigerant therein.

The secondary refrigerant circuit includes a condenser portion and an evaporator portion connected in closed series or orbital relation. In the refrigerating machine shown in the drawings, the evaporator portion of the secondary circuit is formed by a secondary evaporator 33 which is utilized to abstract heat from the cooling compartment 17. The secondary refrigerant evaporator 33 includes a horizontal U-shaped header 34 which is circular in cross-section and extends about at least three side walls of the cooling compartment 17. A plurality of depending U-shaped conduits 35 provide refrigerant circulatory passages communicating with the header 34 below the normal liquid level therein. The refrigerant circulatory conduits 35 are preferably soldered to the metallic liner 18 to provide good thermal contact with the exterior surfaces of the side and rear walls of the liner 18 of the cooling compartment 17. The refrigerant circulatory conduits 35 are distributed over a sufficient portion of the side and rear walls of the liner 18 in order that the entire side and rear wall surfaces of the latter will be maintained at a substantially uniform temperature. The secondary refrigerant circulatory system also includes a secondary condenser 36, which is positioned adjacent a rectangular opening 19a formed in the top of the insulation 19. As best shown in Fig. 4, the secondary condenser 36 includes a smooth top plate 37 made of flexible sheet metal and a corrugated lower sheet 38. The corrugations in the lower sheet 38 cooperate with the smooth upper sheet 37 to define a refrigerant circulatory passage in the condenser 36. The sheets 37 and 38 are secured together about their peripheral edges and along the contacting portions thereof between the corrugations formed in the lower sheet 38 by line welding, a series of closely spaced spot welds, brazing, or in some similar manner. The secondary condenser 36 is supported on four helical compression springs 39 which are located adjacent the corners thereof and connected to the secondary evaporator 33 by flexible conduits so that there will be no interference with the movement of the secondary condenser 36 upon the helical compression springs 39. The lower ends of the compression springs 39 rest on horizontal supports 40 and 41 which are in turn secured at their opposite ends to the outer shell 16 of the lower section of the cabinet.

A series of depending ribs 42 are provided on the lower side of the primary evaporator 29 extending through a rectangular opening 15a formed in the insulation 15 and the opening 12b in the plate 12a, in order to conduct heat from the secondary evaporator 36 to the refrigerant contained in the circulatory passages 31 of the primary evaporator 29. The depending ribs 42 are preferably made of cast iron, or some good heat conducting material, and in the refrigerator illustrated are cast on the lower portions of the refrigerant passages 31 of the primary evaporator 29. A good thermal contact between the ribs 42 and the refrigerant circulatory passages 31 is thus insured.

The lower surfaces of the ribs 42 are so positioned that the springs 38 are partially compressed when the upper section 10 of the cabinet is placed on top of the lower section 11. As a consequence, the heat conducting ribs 42 are pressed into good thermal contact with the upper surface of the secondary condenser 36. Since the sheet 37 which forms the upper surface of the secondary condenser 36 is flexible, it will closely conform to any irregularities in the lower surfaces of the heat conducting ribs 42.

The secondary evaporator 33 is of the flooded type and the header 34 thereof is normally maintained about half full of liquid refrigerant, the circulatory passages 35 thereof being thus maintained flooded. The liquid refrigerant contained in the refrigerant circulatory passages 35 is vaporized by the absorption of heat from the cooling compartment 17 and the bubbles of vaporized refrigerant pass upwardly through the circulatory passages 35 to the header 34 where the vaporized refrigerant is collected above the level of the liquid refrigerant contained therein. The vaporized refrigerant collected in the header 34 passes through a flexible conduit 43, which is connected to the top of the header 34 above the normal liquid level therein, into the circulatory passages of the secondary condenser 36. The gaseous refrigerant thus passing to the secondary condenser 36 is liquefied therein by the transfer of heat therefrom through the ribs 42 to the primary evaporator 29. The secondary condenser 36 is placed at an angle, as illustrated in the drawings, in order that the refrigerant liquefied therein will drain by gravity to the lower end thereof at which an outlet 44 is located. Liquid refrigerant passes from the outlet 44 through a flexible conduit 45 to control valve 46, described more in detail below, and then through a conduit 47 back to the header 34 of the secondary evaporator 33. The secondary evaporator 33 and secondary condenser 36 are thus connected in orbital, or closed series relation.

The freezing compartment 13 and the cooling compartment 17 are provided with openings 48 and 49 which are closed by heat insulated doors 50 and 51, respectively. Articles to be preserved in the respective compartments may be inserted through these openings. A series of wire shelves 52 are supported within the cooling compartment 17 on inwardly projecting shoulders 53 formed in the side walls of the inner liner 18. Trays of water to be frozen, ingredients for ice cream, or the like, may be placed in the freezing compartment 13, as well as meat and similar articles which are best preserved at temperatures below 32° F. The primary evaporator 29 ordinarily maintains the freezing compartment 13 at a temperature below 32° F. usually within the range from 0 to 10° F. Bottles of milk, vegetables, or the like, may be preserved in the cooling compartment 17 at a temperature above 32° F. and below 50° F. I have found 40° F. to be a desirable average temperature for the air in the cooling compartment 17. It will be noted that the secondary evaporator 33 cools the side and rear walls of the liner 18 to a substantially uniform temperature, thus providing a cooling surface of relatively large area in proportion to the cubic contents of the cooling compartment 17. The secondary evaporator also acts as a barrier to heat leaking through the insulation 19 toward the compartment 17. Thus, it is possible to cool the contents of the compartment 17 with a relatively small

temperature differential, that is, in the order of about 5° F., between the compartment and the secondary evaporator 33. Hence, by means of the arrangement described, the interior walls of the compartment 17 may be maintained at a 5 temperature above 32° F. and below 50° F. so that frosting of the walls and hence dehydration of the contents of the cooling compartment 17 is avoided. Dehydration of vegetables and similar articles is of prime importance in their 10 proper preservation since dehydration is one of the principal causes of their wilting and taking on an unpalatable appearance. The problem of maintaining a small temperature differential between the evaporator and the air in the compartment is particularly important in an arrangement in which fresh air is continually admitted to the compartment as hereinafter described.

In the refrigerator shown in the drawings, the 20 primary evaporator 29 is also provided with a relatively large cooling area in proportion to the cubic contents of the freezing chamber 13 in order to reduce the frosting of the walls thereof. That is, if a fixed rate of dehydration is assumed, 25 the thickness of the layer of frost formed on the evaporator will be inversely proportional to its area. It is desirable that the thickness of the frost layer be minimized as the frost obstructs the passage of heat from the air in the compartment to the refrigerant contained in the evaporator.

The amount of liquid refrigerant contained in each of the evaporators may be properly proportioned in order to aid in maintaining the desired differential in temperature between the freezing compartment 13 and the cooling compartment 17, respectively. If sulphur dioxide, for example, is used as the refrigerant in both evaporators the amount of liquid refrigerant in the secondary evaporator 33 may be proportioned with respect to its total volume in such manner that only the lower portions of the conduits 35 are filled with liquid refrigerant. Since the portion of the evaporator 33 containing liquid refrigerant performs the major part of the cooling and this portion of the evaporator is decreased as the amount of liquid refrigerant in the evaporator is decreased, the total amount of heat dissipated from the cooling compartment 17 is 40 decreased and the average temperature prevailing in the cooling compartment is increased. Even when the quantity of refrigerant in the two evaporators are proportioned, as described above in order to maintain the desired differential in 45 temperature between the freezing compartment 13 and the cooling compartment 17, I have found that there is an undesirable interdependence between the temperatures prevailing in these two compartments. That is, when the primary evaporator 29 is subjected to a heavy load due to warm meat, or the like, being placed in the freezing compartment 13, the amount of heat abstracted from the refrigerant contained in the secondary refrigerant circuit is lowered and, as 50 a consequence, the temperature in the cooling compartment 17 rises.

I have provided an arrangement for regulating the temperature of the contents of the cooling compartment 17 irrespective of the temperature prevailing in the freezing compartment 13. This arrangement includes the control valve 46 which regulates the amount of liquid refrigerant flowing to the flooded type secondary evaporator 33 from the secondary condenser 36 in order to 55 70 75

maintain the contents of the cooling compartment 17 at a relatively constant temperature. As best shown in Fig. 2, the control valve 46 includes a cylindrical valve casing 54 having a 5 cylindrical valve seating member 55 rigidly secured in one end thereof. The valve 46 is mounted on the support 41 by a bracket 54a. A valve seat 56 is formed in the valve seat member 55 which cooperates with a cylindrical valve element 10 57 to control the amount of liquid refrigerant flowing from the conduit 45 through the recess 58 formed in the valve seat member 55 to the conduit 47. The butt end of the valve element 57 is rigidly secured to a closed outer end of a 15 flexible metallic bellows 59. The opposite end of the bellows 59 is hermetically sealed to the valve seat body 55. The valve element 57 is loosely mounted in a guide bushing 60 which is rigidly secured in a bore formed in the valve seat 20 member 55 communicating with the recess 58 therein. Liquid or gaseous refrigerant entering the recess 58 from the conduit 45 passes along the groove 57a in the side of the valve element 57 into the interior of the bellows 59. The exterior of the bellows 59 is exposed to atmospheric pressure and when the pressure of the refrigerant contained within the bellows reaches a predetermined value, the bellows is expanded and the valve element 57 retracted from the seat 56, 25 so that liquid refrigerant is permitted to flow past the seat 56 from the conduit 45 into the conduit 47. The pressure of the gaseous refrigerant in the secondary evaporator 33 is transmitted to the liquid refrigerant contained in the secondary 30 condenser 36 since they are in open communication through the conduit 43 and this pressure is in turn communicated through the refrigerant in the conduit 45 and valve 46 to the interior of the bellows 59. In consequence, the valve element 57 is caused to move from a closed to an 35 open position when the pressure and hence the temperature of the secondary evaporator 33 reaches a predetermined value, thus admitting additional liquid refrigerant thereto. When the secondary evaporator 33 reaches a predetermined 40 low value, the pressure therein drops to a corresponding value and the valve element 57 again closes thus shutting off the flow of liquid refrigerant to the secondary evaporator 33. When the valve element 57 is closed liquid refrigerant is 45 accumulated in the secondary condenser 36 and as the condenser fills with liquid, the amount of heat transferred therefrom to the primary evaporator 29 decreases. The accumulation of liquid refrigerant in the secondary condenser 36 decreases the heat transfer to the primary evaporator 29 which raises the vapor pressure in the secondary refrigerant circuit thus minimizing the 50 evaporation of refrigerant in the secondary evaporator 33 and consequently raising the temperature thereof. When the pressure in the secondary refrigerant circuit reaches a predetermined high value the valve element 57 again moves to the open position, as described above, admitting liquid refrigerant to the secondary 55 evaporator 33.

The temperature at which the bellows 59 will cause the valve element 57 to open and close the valve may be regulated from the exterior of the 60 cabinet by a rotatable operating button 61, which is rigidly connected to a rod 62 by a coupling 63. The inner end of the rod 62 is connected to a threaded plug 64 by a screw 65. The plug 64 is threaded in a bushing 66 which is rigidly 65 secured in the end of the valve casing 54. The

inner end of the plug 64 is provided with a bore 67 in which a helical compression spring 68 is mounted. The compression spring 68 bears against a disk 69 rigidly secured to the end of the bellows 59. The position of the plug 64 in the bushing 66 and hence the biasing force exerted by the spring 68 on the bellows 59 may be varied by rotating the operating button 61. As a consequence, the pressure at which the valve element 57 operates may be adjusted in this manner, to obtain the desired temperature in the compartment 17. 10

It is often desirable to preserve butter or similar articles at a temperature above 40° F. but somewhat below room temperature. It is desirable 15 to preserve butter at this higher temperature in order that it will not become too hard for spreading. I have provided a butter compartment 70 within the cooling compartment 17 which includes a cup-shaped shell 71 having spaced sheet 20 metal walls separated by heat insulation 72. The outer wall of the sheet metal shell 71 is welded, or otherwise rigidly secured, to the liner 18 of the cooling compartment 17, the open front side of the butter compartment 70 being closely adjacent the rear side of the door 51. A fresh air inlet 73 is provided in the side of the butter compartment 70 which communicates with the exterior of the lower cabinet section 11. Fresh air may thus enter the butter compartment 70 25 through the air inlet 73 and after passing therethrough flows through the open front of the butter compartment into the cooling compartment 17. An air outlet is provided in the lower rear wall of the compartment 17 by a conduit 74 30 which is provided with a bushing 75 at its inner end mounted in a hole formed in the rear wall of the inner liner 18 and at its outer end with a flared bushing 76 which is secured by a bolt 77 to the exterior shell 16 of the lower cabinet section 40 11. Since the fresh air entering the butter compartment 70 through the air inlet 73 is at room temperature, the air in the butter compartment 70 is maintained at a temperature above that prevailing in the cooling compartment 17 45 and below the ambient temperature of the surrounding air. The warm air flowing from the butter compartment 70 into the cooling compartment 17 is cooled therein and the cold air in the cooling compartment 17 settles to the bottom 50 thereof from which it passes outwardly through the outlet conduit 74. Fresh air is thus continually supplied to the interior of the cooling compartment 17, which aids in maintaining the relative humidity of the air contained therein at a 55 relatively high value, that is, about 85% and dehydration of the contents is minimized. Such ventilation of the cooling compartment also prevents the same from becoming odiferous in that the gases given off by articles being preserved are carried out of the compartment. The removal of such gases also inhibits the decomposition process. Since the circulation of the fresh air through the cooling compartment 17 is carried on through a rather tortuous circuit, first 60 through the butter compartment 70 and then through the cooling compartment 17 and only under the influence of convection, the heat loss from the cold air passing through the outlet conduit 74 is not very great. 65

While I have shown a particular embodiment of my invention in connection with a compression type refrigerating machine, I do not desire my invention to be limited to the particular construction shown and described and I intend, in the 70 75

appended claims, to cover all modifications within the spirit and scope of my invention.

What I claim as new and desire to secure by Letters Patent of the United States, is:

5. 1. A refrigerator comprising a plurality of separable heat insulated cabinet sections provided with communicating openings in their adjacent walls, one of said cabinet sections having a freezing compartment therein, means including a primary evaporator for cooling said freezing compartment, said primary evaporator extending adjacent said opening in said one cabinet section, another of said cabinet sections having a cooling compartment therein, means including a secondary evaporator for cooling said cooling compartment, a secondary condenser, means for connecting said secondary condenser in closed series relationship with said secondary evaporator, and means for resiliently supporting said secondary condenser adjacent said opening in said last mentioned cabinet section in heat exchange relationship with the portion of said primary evaporator adjacent said opening in said one cabinet section. 10
15. 2. A refrigerator comprising a plurality of separable heat insulated cabinet sections provided with communicating openings in their adjacent walls, one of said cabinet sections having a freezing compartment therein, means including a primary evaporator for cooling said freezing compartment, said primary evaporator extending adjacent said opening in said one cabinet section, another of said cabinet sections having a cooling compartment therein, means including a secondary evaporator for cooling said cooling compartment, a secondary condenser, means for connecting said secondary condenser in closed series relationship with said secondary evaporator, and means for resiliently supporting said secondary condenser adjacent said opening in the last mentioned cabinet section in heat exchange relationship with said ribs on said primary evaporator. 20
25. 3. A refrigerator comprising a plurality of separable heat insulated cabinet sections provided with communicating openings in their adjacent walls, one of said cabinet sections having a freezing compartment therein, means including a primary evaporator for cooling said freezing compartment, said primary evaporator extending adjacent said opening in said one cabinet section, another of said cabinet sections having a cooling compartment therein, means including a secondary evaporator for cooling said cooling compartment, a secondary condenser, means for connecting said secondary condenser in orbital relationship with said secondary evaporator, and means including a plurality of compression springs bearing against the one side of said secondary condenser for resiliently supporting the same adjacent said opening in said last mentioned cabinet section in heat exchange relationship with the portion of said primary evaporator adjacent said opening in said one cabinet section. 30
35. 4. A refrigerator comprising a plurality of separable heat insulated cabinet sections provided with communicating openings in their adjacent walls, one of said cabinet sections having a freezing compartment therein, means including a primary evaporator for cooling said freezing compartment, said primary evaporator extending adjacent said opening in said one cabinet section, another of said cabinet sections having a cooling compartment therein, means including a secondary evaporator for cooling said cooling compartment, a secondary condenser, means for connecting said secondary condenser in closed series relationship with said secondary evaporator, and means for resiliently supporting said secondary condenser adjacent said opening in said second cabinet section in heat exchange relationship with a portion of said primary evaporator adjacent said opening in said first mentioned cabinet section. 40
45. 5. A refrigerator comprising a heat insulated cabinet section having a freezing compartment therein, means including a primary evaporator for cooling said freezing compartment, a second heat insulated cabinet section having a cooling compartment therein, means including a secondary evaporator for cooling said cooling compartment, said first mentioned cabinet section being mounted on top of said second cabinet section, each of said cabinet sections having an opening in one wall communicating with an opening in the adjacent wall of the other section, a secondary condenser, means for connecting said secondary condenser in closed series relationship to said secondary evaporator, and means for resiliently supporting said secondary condenser adjacent said opening in said second cabinet section in heat exchange relationship with a portion of said primary evaporator adjacent said opening in said first mentioned cabinet section. 50
55. 6. A refrigerator comprising a plurality of separable superimposed heat insulated cabinet sections provided with communicating openings in their adjacent walls, one of said cabinet sections having a freezing compartment therein, means including a primary evaporator for cooling said freezing compartment, said primary evaporator extending adjacent said opening in said one cabinet section, another of said cabinet sections having a cooling compartment therein, means including a secondary evaporator including a header extending about at least three walls of said cooling compartment and depending refrigerant circulatory passages communicating therewith for cooling said cooling compartment, a secondary condenser, means for connecting said secondary condenser in closed series relationship with said secondary evaporator, said secondary condenser being located adjacent said opening in said second cabinet section in heat exchange relationship with the portion of said primary evaporator. 60
65. 7. A refrigerator comprising a plurality of separable heat insulated cabinet sections provided with communicating openings in their adjacent walls, one of said cabinet sections having a freezing compartment therein, means including a primary evaporator for cooling said freezing compartment, said primary evaporator being provided with a series of heat conducting ribs extending through said opening in said one cabinet section in heat exchange relationship with the portion of said primary evaporator. 70
- 75.

orator adjacent said opening in said first mentioned cabinet section.

8. A refrigerator comprising a heat insulated cooling compartment, means for abstracting heat from the contents of said compartment, a heat insulated butter cooling compartment located within the first mentioned compartment, means including an opening in one wall thereof forming a communicating passage therebetween for conveying restricted quantities of air from said butter cooling compartment to said first mentioned cooling compartment, and means including an air inlet in a wall of said butter cooling compartment and an air outlet in a wall of said first mentioned compartment for ventilating both of said cooling compartments.

9. A refrigerator comprising a plurality of separable heat insulated cabinet sections provided with communicating openings in their adjacent walls, one of said cabinet sections having a relatively low temperature compartment therein, means including a primary evaporator for cooling said relatively low temperature compartment, said primary evaporator extending adjacent said opening in said one cabinet section, another of said cabinet sections having a relatively high temperature compartment therein, means including a secondary evaporator for cooling said relatively high temperature compartment, a secondary condenser, means for connecting said secondary condenser in closed series relationship with said secondary evaporator, and means for

resiliently supporting said secondary condenser adjacent said opening in said last-mentioned cabinet section in heat exchange relationship with the portion of said primary evaporator adjacent said opening in said one cabinet section. 5

10. A refrigerator comprising a plurality of separable heat insulated cabinet sections provided with communicating openings in their adjacent walls, one of said cabinet sections having a relatively low temperature compartment therein, means including a primary evaporator for cooling said relatively low temperature compartment, said primary evaporator extending adjacent said opening in said one cabinet section, another of said cabinet sections having a relatively 15 high temperature compartment therein, means including a secondary evaporator for cooling said relatively high temperature compartment, a secondary condenser, means for connecting said secondary condenser in closed series relationship 20 with said secondary evaporator, means for resiliently supporting said secondary condenser adjacent said opening in said last-mentioned cabinet section in heat exchange relationship with the portion of said primary evaporator adjacent said 25 opening in said one cabinet section, and means including an automatic valve responsive to the pressure in said secondary evaporator for controlling the flow of refrigerant from said secondary condenser to said secondary evaporator. 30

HARLEY H. BIXLER.
